CONTACT TERMINAL

Arthur W. Kimbell, West Newton, Mass., assignor
to United-Carr Fastener Corporation, Cam-
bridge, Mass., a corporation of Massachusetts

Application April 8, 1939, Serial No. 266,887

1 Claim. (Cl. 200—166)

This invention relates to improvements in contact terminals and particularly to terminals used in connection with switches for radio receivers and the like apparatus where a large number of circuits must be connected and disconnected.

The chief object of my invention is the provision of a contact terminal of simple construction capable of being manufactured inexpensively in large quantities and adapted to grip effectively a cooperating terminal part so as to establish a good electrical contact between the parts.

Referring to the drawing, in which I have illustrated preferred embodiments of my invention:

Fig. 1 is a plan view showing a stator plate commonly used as part of a multiple circuit switch of well-known construction, a rotor plate positioned within the stator plate, and my first form of improved contact terminals mounted upon the stator plate for cooperative electrical engagement with a rotor blade provided by the rotor plate;

Fig. 2 is a plan view of the preferred blank from which my first form of contact terminal is formed;

Fig. 3 is a sectional view taken along the line 3—3 of Fig. 1;

Fig. 4 is a sectional view taken along the line 4—4 of Fig. 1;

Fig. 5 is a perspective view of my first form of improved contact terminal per se; and

Fig. 6 is a sectional view similar to Fig. 3 illustrating the construction of my second form of contact terminal.

Referring in detail to the drawing, I have shown a section of a multiple contact switch with which I have chosen to illustrate the use of my improved contact terminal. Thus I have illustrated in Fig. 1 a stator plate 1 which may be the end one of a switch device having a number of stator plates disposed in spaced relation and maintained in assembly through means such as bolts 2 and 3 extending through the same. The stator plate 1 has a central opening 4 within which is disposed a rotor plate 5. The rotor plate 5 carries one or more rotor blades 6 which project beyond the outer edge of the rotor plate and are secured to the rotor plate through attaching portions 7 extending into fastener engagement with the plate 5 through apertures 8. The stator plate 1 carries a suitable number of my improved contact terminals 9 which provide contact portions disposed within openings 10 of the stator plate for electrical

engagement with the rotor blade 6 during rotation thereof, as will be understood by those skilled in the art. The rotor plate 5 is turned relative to the stator plate by means of a non-circular shaft 11 projecting through a similarly-shaped opening 12 of the rotor plate.

Referring in detail to my first form of improved contact terminal, I have shown in Fig. 2 a preferred form of blank from which my completed terminal is formed. The blank preferably comprises two elongated strips of metal 13 and 14 disposed in spaced parallel relationship. The strips 13 and 14 are preferably of equal length whereby when one of the strips is folded 15 into superposed relation to the other of the strips, the body of the terminal will be of double thickness substantially from one end to the other. The strips 13 and 14 are connected together by a connecting portion 15 (Figs. 2, 3, and 5) integrally joined to inner longitudinal edges 16 and 17 of the strips intermediate the ends thereof. The strips 13 and 14 have apertures 18—18 adjacent one end adapted to be aligned, when the strips are in folded relation, providing an opening 19 for receiving lead wires prior to soldering of the wires to the terminal and apertures 20—20 are provided at substantially the centers of the strips for alignment, after the strips have been disposed in folded relation, providing an opening 21 to receive an attaching rivet 22 whereby the terminal may be secured to the stator 1.

My improved contact terminals are formed from a blank, such as illustrated in Fig. 1, through folding the blank along the dotted line 23 of the connecting portion 15 thus moving the strip 13 transversely of the strip 14 to dispose the strips in superposed relation.

Each of my first form of terminals 9 comprises an attaching portion 24 having the strips 13 and 14 in contiguous relation. The connecting portion 15 joins adjacent edges of the strips 13 and 14 at one side of the attaching portion 24, as most clearly shown in Figs. 4 and 5. The opening 21 receives the rivet 22 so as to secure the terminal to the stator 1, as most clearly shown in Figs. 3 and 4. A wire-securing portion 25 extends in upward angular relation from one end of the attaching portion 24 and has the strips 13 and 14 in contiguous relation in my first form of contact terminal, as most clearly shown in Fig. 3. The wire-securing portion 25 preferably has the opening 19 for receiving and maintaining lead wires (not shown) in temporary fixed engagement with the terminal prior

to soldering the wires thereto. A contacting portion 26 extends from an opposite end of the attaching portion 24 from the wire-securing portion 25 and provides a pair of contact-engaging jaws 27-27 which flare outwardly on opposite sides of the terminal. The jaws 27-27 are adapted to receive the rotor blade 6 between them and grip the same, as most clearly shown in Fig. 3, so as to effect good electrical connection between the parts.

Referring to my second form of invention illustrated in Fig. 6, I have shown a contact terminal having a wire-securing portion 28 which differs in form from the wire-securing portion 25 of my first form through providing means whereby a lead wire (not shown) may be inserted between inner broad faces of the strips 13 and 14 and maintained between the same until fixed in final secured engagement with the terminal through any suitable means such as solder or 15 spot-welding. Thus the outer end 29 of the upper strip 13 is flared outwardly from the strip 14 providing a lead for receiving a lead wire between the strips. The upper strip 13 extends inwardly from the flared portion 29 into adjacent 20 relation with the strip 14 and then outwardly forming a shoulder 30, behind which the lead wire is engaged. An opening 31 may be provided in the upper strip 13 adjacent the shoulder 30 enabling solder to be applied to the lead wire for 25 soldering the same to the inner broad surface of the strip 14.

Thus it will be seen that by my invention I have provided a contact terminal of simple and inexpensive construction having a body comprising doubled strips which are connected at their side edges. My improved construction is readily adapted to use for a purpose shown by the second form of my invention wherein it is desired to secure a lead wire in temporary attachment to the terminal through a spring fastener means provided by the terminal.

Although I have illustrated and described preferred forms of my invention, I do not wish to be limited thereby because the scope of my invention is best defined by the following claim.

I claim:

A one-piece contact terminal for an electrical unit, said terminal having two elongated strips of metal in superposed relation, a connecting portion integral with said strips at adjacent longitudinal edges intermediate the ends thereof for connecting said strips, said terminal having an attaching portion for securing said contact to a supporting part, a wire-securing portion extending from said attaching portion at one end, said wire-securing portion having means between said strips thereof for maintaining a lead in initial assembly with said terminal, and a contacting portion at the other end of said attaching portion, said contacting portion having means for electrical engagement with a cooperating member.

ARTHUR W. KIMBELL.
